Fig. 4

Fig. 5

Fig. 6

FIG. 1 is a front elevational view of an outdoor broiler grill embodying our new design, shown positioned upon a mounting post.

FIG. 2 is a top plan view.

FIG. 3 is a rear elevational view.

FIG. 4 is a right side elevational view.

FIG. 5 is a left side elevational view.

FIG. 6 is a perspective view of the outdoor broiler grill with the holes in the top portion being fragmentally shown for convenience of illustration only.

The post shown in broken lines is included for illustrative purposes only.

We claim:

The ornamental design for an outdoor broiler grill or the like, as shown and described.
